CHIMNEY SPARK ARRESTER

Frank Carpino, 1875 Funston St., Stockton, Calif.

Filed Sept. 4, 1964, Ser. No. 81,593

Term of patent 14 years

(Cl. D62—3)

FIG. 1.

FIG. 2.

FIG. 4.

FIG. 5.

FIG. 6.

FIGURE 1 is a plan view of a chimney spark arrester showing my new design;

FIGURE 2 is a side elevational view, the side opposite thereto being substantially similar in appearance;

FIGURE 3 is a front elevational view as seen from the right of FIGURE 2, the side opposite being substantially similar in appearance;

FIGURE 4 is a cross sectional view, the plane of section being on the line 4—4 of FIGURE 3;

FIGURE 5 is a cross sectional view, the plane of section being on the line 5—5 of FIGURE 3; and

FIGURE 6 is a cross sectional view, the plane of section being on the line 6—6 of FIGURE 3.

I claim:

The ornamental design for a chimney spark arrester, as shown and described.
